Primary Examiner—Robert M Spear*Assistant Examiner*—Rashida C McCoy(74) *Attorney, Agent, or Firm*—Gifford, Krass, Sprinkle, Anderson & Citkowski, P.C.; Douglas L. Wathen(57) **CLAIM**

The ornamental design for a shoe, as shown and described.

DESCRIPTION

FIG. 1 is a perspective view of a shoe, showing my new design;

FIG. 2 is a top view thereof;

FIG. 3 is a side elevation view thereof;

FIG. 4 is a bottom view thereof;

FIG. 5 is an opposite side elevation view thereof;

FIG. 6 is a front elevation view thereof; and,

FIG. 7 is a rear elevation view thereof.

The broken line showing of the footwear illustrates environmental structure and forms no part of the claimed design.
